UNITED STATES PATENT OFFICE.

JOHN H. RAYMOND, OF SYRACUSE, NEW YORK.

IMPROVEMENT IN ASH-SIFTERS.

Specification forming part of Letters Patent No. 178,381, dated June 6, 1876; application filed March 25, 1876.

To all whom it may concern:

Be it known that I, JOHN HENRY RAYMOND, of Syracuse, in the county of Onondaga and State of New York, have invented a new and Improved Ash-Sifter, of which the following is a specification:

In the accompanying drawing, Figure 1 represents a vertical longitudinal, and Fig. 2 a vertical transverse section, of my improved ash-sifter, respectively, on the lines *x x*, Fig. 2, and *y y*, Fig. 1.

Similar letters of reference indicate corresponding parts.

The invention consists in an outer receptacle having circular guide-grooves in connection with a swinging cover of arch form, and having lateral end flanges, as hereinafter described.

In the drawing, A represents a receptacle that is made in the shape of a coal-scuttle, with bail for carrying the same. At the inside of receptacle A is a cylindrical drum, B, of perforated or reticulated sheet metal, said drum revolving by shaft and hand-crank in perforations of the receptacle. The sifting-drum B is made of a fixed section, C, and a swinging section, C', the latter sliding in guide-grooves *a* of the side walls of the drum, so as to be readily opened or closed. The sliding section C' is locked by a suitable catch device to the fixed section of the drum when the ashes are placed into the same. An arc-shaped cover, D, is guided in circular grooves *b* of the side walls of the receptacle A, which grooves are concentric to the shaft of the drum, and carried by a knot, *d*, of its lateral flange part D', either into po-

sition below the drum, to admit the opening of the same and putting in of the ashes, or into closed position above the same for sifting. When the cover is closed over the drum the same is revolved, so that the ashes are separated from the coal particles and dropped to the bottom of the receptacle. The flange D' of the core D bears, when the cover is in open or closed position, against the walls of the receptacle and prevents the escape of dust. When the ashes are sifted the cover is thrown open, as shown in Fig. 1. The drum is also opened, and the coal remaining therein removed, by holding the drum and tilting the receptacle, the coal passing over the flange and spout to a pail or other receptacle. The ashes are removed by closing the cover and allowing them to pass out between the drum and receptacle.

The ashes may, by this sifter, be separated in a convenient manner from the unburned coal, without the annoyance of the present sifting. The entire sifter is made of sheet metal, which allows the sifting of hot ashes without danger.

Having thus described my invention, I claim as new and desire to secure by Letters Patent—

The combination, in an ash-sifter, of a swinging arc-shaped cover, having lateral end flanges, and an outer receptacle, having circular guide-grooves, substantially as and for the purpose specified.

JOHN HENRY RAYMOND.
